United States Patent

Des. 236,189
Patented Aug. 5, 1975

236,189

DIGITAL CLOCK OR SIMILAR ARTICLE

Theodore G. Daher, Stratford, Conn., assignor to
General Electric Company

Filed Jan. 28, 1974, Ser. No. 437,540

Term of patent 14 years

Int. Cl. D10—01

U.S. Cl. D10—15

FIG. 1.

FIG. 2.

FIG. 3.

FIG. 4.

FIG. 5.

FIG. 6.

FIG. 1 is a left front perspective view of a digital clock or similar article showing my new design;

FIG. 2 is a front elevational view thereof;

FIG. 3 is a top plan view thereof;

FIG. 4 is a rear elevational view thereof;

FIG. 5 is a bottom plan view thereof; and

FIG. 6 is a right side elevational view thereof.

I claim:

The ornamental design for a digital clock or similar article, substantially as shown.
